(57) **CLAIM**

I claim the ornamental design for an electronic cigarette, as shown and described.

DESCRIPTION

FIG. 1 is a perspective view of an electronic cigarette according to an embodiment.

FIG. 2 is a front view of the electronic cigarette depicted in FIG. 1.

FIG. 3 is a back view of the electronic cigarette depicted in FIG. 1.

FIG. 4 is a right side view of the electronic cigarette depicted in FIG. 1.

FIG. 5 is a left side view of the electronic cigarette depicted in FIG. 1.

FIG. 6 is a top view of the electronic cigarette depicted in FIG. 1.

FIG. 7 is a bottom view of the electronic cigarette depicted in FIG. 1.

FIG. 8 is a detail view of section A indicated in FIG. 1; and, FIG. 9 is a detail view of section B indicated in FIG. 2.

Items shown in broken lines indicate the environment in which the electronic cigarette is associated. Portions of the drawings that are shown in broken lines form no part of the claimed design.

1 Claim, 3 Drawing Sheets
